UNITED STATES PATENT OFFICE.

WILLIAM TELFORD AND ROBERT J. MCLEAN, OF PARACALE, PHILIPPINE ISLANDS.

CLAY-DISINTEGRATING MACHINE FOR SLUICE-BOX DREDGES.

1,377,034.

Specification of Letters Patent.

Patented May 3, 1921.

Application filed October 6, 1920. Serial No. 415,111.

To all whom it may concern:

Be it known that we, WILLIAM TELFORD and ROBERT J. MCLEAN, of the Commonwealth of Australia, residing at Paracale, in the Philippine Islands, have invented certain new and useful Improvements in a Clay-Disintegrating Machine for Sluice-Box Dredges; and we do hereby declare the following to be a full, clear, and exact description of the invention, such as will enable others skilled in the art to which it appertains to make and use the same.

The present invention relates to improvements in gold saving devices to be used on a dredge or other mining class of sluice-box where clay which steals gold prevails.

An object of the invention is to provide an improved device of this character which involves a clay disintegrating device placed in the sluice-box and partaking of a circular movement in which the beaters or breakers are prevented from swinging outwardly due to centrifugal force, but may yield in the direction of movement as required when rocks or other hard substances are encountered.

With the foregoing and other objects in view, the invention will be more fully described hereinafter, and will be more particularly pointed out in the claims appended hereto.

In the drawings, wherein like symbols refer to like or corresponding parts throughout the several views,

35 Figure 1 is a view in side elevation with parts shown in section of an improved clay disintegrating device constructed in accordance with the present invention;

Fig. 2 is a plan view of the beater disk;

40 Fig. 3 is a central sectional view taken on the line 3-3 in Fig. 2;

Fig. 4 is an edge view of one of the link beaters;

Fig. 5 is a plan view of the same; and

45 Fig. 6 is a cross sectional view taken on the line 6-6 in Fig. 5.

Referring more particularly to the drawings, 1 designates generally a framework employed in connection with sluice-boxes, 50 and 2 and 3 represent the side walls forming the sluice way indicated at 4.

Cross beams 5 and 6 form parts of the frame and support bearings 7 and 8 in which a vertical shaft 9 is journaled. A 55 bevel gear wheel 10 is fixed to the upper end of the shaft 9 and is disposed in mesh

with a similar bevel pinion 11 on a drive shaft 12 which receives rotation from a suitable source of power. One or more appropriate bearings 13 are provided in which 60 to journal the drive shaft 12.

A coupling piece 14 having a flange 15 is mounted on the lower end of the shaft 9 and turns therewith. Bolts 16 pass through the flange 15 and through the beater disk 17 65 which is preferably made from hard wood and is reinforced by a pair of outer rings 18 and 19 and by inner rings 20 and 21, as more particularly seen in Figs. 2 and 3.

Beaters are secured to the under face of 70 the disk 17 and are preferably composed of links 22 set with their connecting pins 23 extending in a radial direction, whereby to prevent the link beaters from swinging outwardly due to the centrifugal force developed by the rotation of the disk 17, and at the same time permitting of the yielding of the beaters in the direction in which the circular movement is taking place.

Heads 24 are bolted or otherwise secured 80 to the under face of the disk 17 in order to support the link beaters. These beaters are preferably made of cast manganese and are preferably twelve in number being situated apart at suitable intervals about the 85 edge of the disk. However, these beaters may be provided in suitable numbers as desired by the character of work to be performed or the amount of such work.

The lowermost links of the beaters carry 90 transverse pins 25 on which are mounted cutters 26 preferably of square or rectangular form and having the corners thereof projecting in offset relation to the corners of adjacent disks so as to provide a substantially star-like cutting device looked at 95 from the side as appears in Fig. 4. Spacing lugs 27 are provided between the cutters 26.

In operation the drive shaft 12, through 100 the pinion 11 and gear wheel 10, imparts rotation to the shaft 9 which carries with it the disk 17. In this way the beaters are caused to rotate about in the sluice box and to come in contact with the clay and other 105 matter passing therethrough.

As before described the cutters and chain links will be permitted to yield in the direction in which the circular movement is taking place in order to prevent injury to these 110 members by rocks or other hard substances, but such links are prevented from being

thrown out by the action of centrifugal force which would cause the cutters 26 to be removed from a position adjacent the bottom of the sluice and to be thrown against 5 the side walls 2 and 3.

It is obvious that various changes and modifications may be made in the herein described apparatus without departing from the spirit of the invention, provided such 10 changes and modifications fall within the scope of the appended claims.

What is claimed is:

- 15 1. In a disintegrating machine, the combination of rotary supporting means, and cutting members extending downwardly from the supporting means and composed of a plurality of chain links having their pivots arranged radially to permit swinging of the members in the direction of their movement but acting to prevent their swinging outwardly by centrifugal force, substantially as described.
- 20 2. In a disintegrating machine, rotary supporting means, disintegrating members extending downwardly from the supporting means near its outer edge, said members composed of a plurality of links having their pivots extending in a substantially radial direction, and cutting members carried by the lowermost link, substantially as described.
- 25 3. In a disintegrating machine, rotary supporting means, disintegrating members depending from said supporting means and mounted in spaced relation about the same near its outer edge, said members composed of interconnected links, and spaced apart cutting disks carried by the lowermost link, substantially as described.
- 30 4. In a disintegrating machine, rotary supporting means, disintegrating members extending downwardly from the supporting means, said members being disposed in spaced and circular relation about the outer portion of the supporting means, said mem-

bers composed of a plurality of chain links having their pivot points disposed radially, and a plurality of rectangular cutting disks carried by the lower end of said members, substantially as described.

5. In a disintegrating machine, the combination of container for the material, a head rotating thereabove, disintegrating members extending downwardly from said head and composed of a plurality of chain 55 links having their pivot points directed radially to the direction of their movement, and rectangular cutting disks carried by the lower ends of said members and having their corners or points disposed in offset relation, 60 substantially as described.

6. In a disintegrating machine, a rotating disk, reinforcements for the upper and lower edges of the disk, means for imparting rotation to said disk, and flexible disintegrating members extending downwardly from the disk near its outer end and in spaced relation, substantially as described.

7. In a disintegrating machine, the combination of a disk, a circular shaft carrying 70 said disk and adapted to rotate the disk in a substantially horizontal plane, gear means for driving the shaft, means for reinforcing the disk, and depending chain members on said disk having their pivot points directed 75 radially and adapted to yield in a circumferential direction, and spaced apart rectangular cutting disks carried by the lower ends of said members with their points relatively offset and arranged in gangs, substantially as described.

In testimony whereof, we have hereunto affixed our signatures, in the presence of two witnesses.

WM. TELFORD.
R. J. McLEAN.
